UNITED STATES PATENT OFFICE.

MARY Y. HARMON, OF LAGUNA BEACH, CALIFORNIA.

BATIK-FRAME SUPPORT.

Application filed September 16, 1926. Serial No. 135,896.

This invention relates to a support for batik frames, and an object is to provide an adjustable support that in addition to holding batik frames in horizontal or tilted positions, can also be moved up or down so that the work can be arranged within convenient reach of an artist in either a standing or seated position.

An object of the invention is to provide a support for holding frames of various sizes; and to that end I provide an appliance with radially extending arms that are adjustable so that they can be lengthened or shortened to hold large, intermediate or small batik frames.

Another object is to provide a support for holding the batik frames so that they can be revolved on an axis for various purposes such as turning the frame to bring remote points of the material closer to an artist or spinning the frame to paint, pencil or wax circular lines or bands on the material.

Another object of the invention is to provide means for saving time and labor; and to that end I provide an appliance that enables an artist to accomplish a larger amount of work in a much shorter time and with less arduous labor than can be performed without the aid of this appliance.

A feature of the invention is shown in the means employed for detachably connecting the batik frames to the support, whereby they are securely held in place; but can easily be removed from or secured to the support.

Other objects, advantages and features of the invention may appear from the accompanying drawings, the subjoined detailed description and the appended claims.

The accompanying drawings illustrate the invention, in which:

Figure 1 is a side view of a support for a batik frame constructed in accordance with this invention, showing it arranged holding a batik frame in a horizontal position with material stretched thereon, and also showing by dotted lines a tilted or inclined position of the support and frame; Fig. 2 is a fragmental plan view of a batik frame on a support, with batik material stretched thereon; Fig. 3 is an enlarged fragmental section on line 3—3 of Fig. 2 showing a detail of the means for securing the batik material to the frame; Fig. 4 is a view analogous to Fig. 1 showing the support adapted to be attached to the edge of a table, and

arranged to incline the batik frame; Fig. 5 is a plan view of the support with a batik frame thereon ready to have the batik material attached thereto; Fig. 6 is a cross section on line 6—6 of Fig. 5, showing a detail of one of the supporting arms; Fig. 7 is a cross section on line 7—7 of Fig. 5, showing a detail of the means for detachably securing the batik frame to the supporting arms; Fig. 8 is a vertical section on line 8—8 of Fig. 5 showing a detail of the support construction; Fig. 9 is a cross section on line 9—9 of Fig. 8; Fig. 10 is a section on line 10—10 of Fig. 7 showing a fragmental plan view of one of the supporting arms and a pin carrying spool.

The support comprises a grooved post 12 having a base 13 that is adapted to hold the post in an upright position. This post 75 has a vertically extending dovetailed groove 14 in which an adjustable post 15 is slidably fitted, and adapted to be raised or lowered relative to the post 12 to raise or lower a batik frame to any desired position, and 80 a set screw 16 is arranged to hold the posts in relatively fixed position when properly adjusted.

The post 15 has a slotted upper end into which is fitted a tongue 17 of a head 18. 85 The tongue 17 is pivotally connected to the post 15 by a bolt 19; and a wing nut 20 is provided for the bolt 19 so that when tightened the tongue 17 and forked end of the post 15 will be secured together to prevent 90 pivotal movement of the tongue on the bolt. In other words the nut 20 is loosened when the head 18 is to be adjusted, and tightened when it is to be held in a fixed position on the post.

A bearing pin 21 has its upper end headless, as shown, and its lower end secured in the upper end of the head 18; and a body 22 having a socket 23 is detachably and loosely mounted on the headless end of pin 100 21 and is arranged to be revolved either slowly or rapidly thereon. This permits quick mounting of the batik frame on the support and free movement thereof and its quick removal.

The body 22 has four radially extending arms 24 that can be integral with the body; and these arms are provided with dove-tailed grooves 25 in which other arms 26 are slidably mounted.

The arms 26 are adapted to be moved radially toward or from the axial center of the

body 22 to adjust them to predetermined positions to hold various sized batik frames; and they are held in adjusted position by set screws 27.

5 Each of the arms 26 has a socket 28 at its outer end in which a cylindrical spool 29 is loosely and removably fitted; and these spools are arranged to extend a slight distance above the upper surface of the arms 10 and each carries a bearing pin 30.

The batik frame comprises the parts 31, 32, 33 and 34, each of which has a number of bearing holes 35 arranged in the end portions thereof through which the pins 30 are 15 adapted to extend to hold the parts together in a rectangular form, as best shown in Fig. 5. As seen therein a frame of intermediate size is formed by arranging the arms 26 so that the pins 30 will extend through intermediate holes in the pieces.

The frame can be increased or decreased in size by loosening the set screws 27 and adjusting the arms 26 so that the pins 30 will be extended through holes nearer the ends 25 or cross centers of the pieces 31, 32, 33 and 34. The batik frame comprising the four pieces above mentioned is preferably rectangular in cross section and formed of light soft wood so that the batik material 36 stretched thereon can be secured thereto by thumb tacks 37 as indicated in Figs. 1 and 30 4; and shown in detail in Figs. 2 and 3. While I have shown thumb tacks for securing the cloth, canvas or material to the batik 35 frame, it is understood that I may employ other means such as securing tape to the pieces so that the material can be pinned on as is now commonly practiced in the art.

Also it is understood that the pieces 31, 40 32, 33 and 34 need not be detachable from one another but they can be connected, in which event I will employ a number of united frames of various sizes that can be provided with holes 35 arranged to register 45 with the pins 30.

In Fig. 4 I provide a bracket 112 for supporting the adjustable post 15; and this bracket is constructed so that it can be detachably connected to a projection 113 such 50 as the ledge of a table 114.

When the bracket 112 is used all the other parts of the support are substantially like those heretofore described and operate the same except the adjustable post 15 which has 55 its lower portion cylindrical so that in ad-

dition to being adjusted upward and downward through the bracket 112 it can also be turned on its longitudinal axis for the purpose of turning the batik frame in a position to obtain suitable light for painting on the material attached to the frame. This form of construction is best adapted for supporting canvas frames and the like on which pictures are being inscribed, washed, penciled or painted; and also it is understood 60 that the support is adapted for supporting light drawing boards.

In operation the parts are adjusted to proper position for receiving a batik frame with material thereon, and arranged so that 70 it is convenient for an artist to paint, print or work thereon; and as described the support is provided with means for holding the frame horizontally or in a tilted or inclined position and revolving it, so that in addition 75 to convenience in operation the appliance is a great time saver in that the artist can accomplish his work in less time and more efficiently and effectively than heretofore.

The invention claimed is:

1. A batik frame construction including a post, an oscillatable head mounted on said post with a pin extending upward therefrom, a frame supporting body with a central hole adapted to fit and turn on said pin 80 and said body having four rigid radially extending arms equidistant from each other, outer arms slidably dove-tailed in connection with said rigid arms and so as to be in alignment therewith, means for securing said 85 slidable outer arms on said rigid arms when adjusted in position, an upwardly extending pin in the outer end of each outer sliding arm, and four batik frame bars with a series of holes near each of their ends adapted to fit on the outer ends of said arms, said frame bars overlapping each other at their 90 ends and forming a rectangular frame.

2. Means for supporting a batik frame and the like, as set forth in claim 1, the outer 100 ends of said slideable arms having round vertical sockets, cylindrical spools loosely fitting in said sockets, and pins mounted in said spools and extending above the same so as to receive the perforated end portions 105 of overlapping batik frame bars, substantially as set forth.

In witness whereof, I have hereunto affixed my signature.

MARY Y. HARMON. 110
